UNITED STATES PATENT OFFICE.

FREDERICK D. LANGENHEIM, OF PHILADELPHIA, PENNSYLVANIA.

FEED-WATER HEATER.

SPECIFICATION forming part of Letters Patent No. 412,927, dated October 15, 1889.

Application filed March 29, 1889. Serial No. 305,211. (No model.)

To all whom it may concern:

Be it known that I, FREDERICK D. LANGENHEIM, a citizen of the United States, and a resident of the city and county of Philadelphia, 5 State of Pennsylvania, have invented a new and useful Improvement in Feed-Water Heaters, of which the following is a true and exact description, due reference being had to the drawings which accompany and form part 10 of this specification, and in which similar letters denote similar parts.

My invention relates to that class of feed-water heaters where the waste products of combustion from the boiler or furnace are 15 used to heat the incoming water to the boiler; and my improvement consists in certain constructions and combinations of parts, which will be hereinafter described, whereby the incoming water is admitted to the boiler 20 highly heated and deprived of its sedimentary deposit.

In the drawings, Figure 1 represents in elevation my improved device, partly in section. Fig. 2 is a side elevation partially in section. 25 A represents the flue leading from the boiler or furnace to the stack through which the waste products of combustion are carried off. B represents a frame-work in this flue, having cross-beams b b' b^2 b^3 at different levels. 30 On these beams are placed water-receptacles C' C² C³ C⁴, preferably cylindrical in shape and made of light boiler-iron or any other proper material. As may be seen, these receptacles are arranged above each other and 35 staggered.

D is the inlet water-pipe from the source of supply, and E the outlet-pipe from the heater to the boiler.

c are the brackets upon which the water receptacles of the heater are placed and through 40 which they are secured to the beams b b' b^2 .

F, F', F², and F³ are pipes leading from one receptacle to the other.

G are blow-off pipes, and g the connections 45 for the blow-off pipes with the water-receptacles.

The water-receptacles C' C² C³ C⁴ are preferably made of size sufficient to admit their being entered and cleaned.

50 The operation is as follows: The water en-

ters through the inlet-pipe D and passes through the receptacles C. It then passes by the pipe F to the receptacle C', returning through said receptacle to its end, then through pipe F' to receptacle C², then through 55 receptacle C² to its end, then through pipe F to receptacle C³, then through receptacle C³, then through the pipe F³ to receptacle C⁴, then through receptacle C⁴ to its end, and then through outlet-pipe E to the boiler.

60 By my improved construction the water is passed through a series of large receptacles, which practically act as settling-tanks, and at the same time the water is highly heated. Again, this construction causes the receptacles to be in different planes, and therefore all the waste products of combustion act upon the water to be heated. Again, the position of the receptacles in relation to each other being staggered, they are more completely 65 acted upon by the products of combustion.

I do not intend to limit myself to any specific number of receptacles, as they may vary in number from that shown in the drawings; 70 nor do I intend to limit myself to the exact arrangement of receptacles shown in the drawings.

Having now fully described my invention, what I claim, and desire to protect by Letters Patent, is—

1. A feed-water heater consisting of a number of drums arranged one above the other, pipes connecting said drums at their ends in a continuous series, said pipes being located 85 above the bottoms of the drums, so that the lower portions of the latter shall serve as settling-chambers, a water-exit pipe leading from the last or uppermost drum of the series, and a water-supply pipe leading to the first or 90 lowermost drum thereof, substantially as described.

2. A feed-water heater consisting of a number of drums arranged one above the other, pipes connecting said drums at their 95 ends in a continuous series, said pipes being located above the bottoms of the drums, so that the lower portions of the latter shall serve as settling-chambers, a water-exit pipe leading from the last or uppermost drum of 100

the series, and a water-supply pipe leading to the first or lowermost drum thereof, and blow-off pipes at the bottom of the several drums, substantially as described.

5. 3. The combination, with the flue A, of cross-pieces or girders one above the other therein, saddles e, located upon said girders, and a series of drums supported in said saddles and connected end to end in a continuous series and provided with a water-supply pipe and a water-exit pipe, substantially as described.

4. A feed-water heater consisting of a number of drums located in pyramid arrange-

ment within a heating-flue, a water-supply pipe connected to one of the lower drums and a water-exit pipe to the uppermost drum, and pipes connecting said drums in a continuous series, said pipes opening into the heads of the drums at substantially the center of said heads, substantially as described.

In testimony of which invention I have hereunto set my hand, at Philadelphia, Pennsylvania, this 25th day of March, A. D. 1889.

FREDERICK D. LANGENHEIM.
